FABRICS AND METHOD OF MAKING THE SAME

Charles Eugene Neisler, Jr., Kings Mountain, N. C., assignor to Neisler Brothers, Incorporated, a corporation of North Carolina

Application June 9, 1953, Serial No. 360,435

14 Claims. (Cl. 139—410)

This invention relates generally to improvements in fabrics and method of making the same and, more particularly, to improvements in inflatable mattress fabrics and method of making the same.

Mattress fabric generally is formed of a pair of woven laterally spaced fabrics interconnected by intermediate threads extending therebetween, the length of the latter between connected portions thereof determining the spacing apart of said pair of fabrics with said spacing being limited to a maximum substantially corresponding to the width of the series of gages on the loom. It is accordingly the primary aim and object of the present invention to provide mattress fabric formed of a pair of fabrics which are spaced apart a distance substantially greater than the width of the series of gages on the loom on which said fabric is made.

It is a further object of the present invention to provide mattress fabric of the aforesaid character which readily lends itself to the formation of inflatable containers, for example, said containers using less material for a given volume than heretofore used containers of this character.

It is yet another object to the present invention to provide an improved method of making the fabric material of the aforesaid character, said method utilizing conventional apparatus in its entirety.

The above and other objects, features and advantages of the present invention will be more fully understood from the following description considered in connection with the accompanying illustrative drawings.

In the drawing which illustrates the best modes now contemplated by me for carrying out my invention:

Fig. 1 is a diagrammatic view of a loom illustrating one step in the formation of the fabric material of the present invention;

Fig. 2 is a view similar to Fig. 1 illustrating a further step in the formation of the fabric material;

Fig. 3 is a view similar to Fig. 2 illustrating still another step in the formation of the fabric material;

Fig. 4 is a view similar to Fig. 3 illustrating yet another step in the formation of the fabric material;

Fig. 5 is a diagrammatic view of the fabric material illustrating the step of expanding the spacing of the component fabrics thereof;

Fig. 6 is a view similar to Fig. 5 illustrating a modified method of making a fabric material; and

Fig. 7 is a fragmentary top plan view of the fabric material formed according to the present invention.

Referring to the drawing in detail, and more particularly to Fig. 5 thereof, the mattress fabric 10, formed according to the present invention, comprises a pair of woven fabrics 12 and 14 having an intermediate thread 16 extending therebetween and woven thereto, said pair of fabrics being disposed in laterally spaced confronting disposition with the intermediate thread 16 being transversely disposed between the fabrics 12 and 14. In accordance with the present invention means are provided for temporarily supporting the thread 16 inter-

2

mediate woven portions thereof relative to the pair of fabrics 12 and 14 so that on the release of said intermediate portions from temporary support the spacing between the fabrics 12 and 14 may be increased from the spacing indicated at 10' to the spacing indicated at 10. One form of method of making the mattress fabric 10 will now be described in detail, said method utilizing conventional apparatus in its entirety.

Thus the loom 20 shown in the drawing is conventional

10 in all respects and is provided with a series of gages 22 which are disposed warp-wise thereof, said gages being supported by the support members 24 and 26 in a conventional manner. Ground warp threads A, B for the top fabric 12 are shown passing over the guiding roller 28 and about the guiding roller 30 and similarly ground warp threads C, D for the bottom fabric 14 are shown passing over the guiding roller 32 and about the guiding roller 34. A suitable thread supply will be provided for the formation of the intermediate warp thread 16, the thread E supplied thereby being illustrated passing over the roller 36. In the illustrated embodiment the intermediate thread E is shown associated with heddle 40, thread A is shown associated with heddle 42, thread B is shown associated with heddle 44, and thread C is shown associated with heddle 46, and thread D is shown associated with the heddle 48, said heddles being diagrammatically illustrated in Figs. 1 through 4. Each of the heddles is provided with suitable eyes and the threads of the fabric 10 pass through said eyes. Each of the 15 series of heddles which carry the threads as aforesaid is provided with its separate harness frame (not shown) and is operated by any suitable conventional mechanism, in accordance with the weave desired. A reed 50 is provided on a swinging lay 52 and said apparatus operates 20 in the conventional manner as will be readily apparent to those skilled in the art. It will be understood that the weaving of the mattress fabric 10 takes place at area 54 of the series of gages 22 and the latter determine the spacing apart of the fabrics 12 and 14. Thus in 25 conventional weaving of mattress fabric the distance between the fabrics 12 and 14 will substantially correspond to the width of the series of gages 22 and in accordance with the present invention means are provided to substantially increase said distance or spacing.

The threads A and B are adapted to be interwoven on loom 20 to form the fabric 12 and the threads C and D are adapted to be interwoven on said loom to form the fabric 14, the intermediate warp thread E being interwoven with the threads A, B, C and D in a manner to be described in detail hereinafter. The weft threads G are interlaced with the warp threads A, B, C and D in a conventional manner whereas the weft threads F are adapted to temporarily support the intermediate thread E relative to the fabrics 12 and 14. In Fig. 1 heddles 40, 42 and 44 are shown positioned so as to define a shed 60 and the weft thread F is thrown through said shed by a shuttle in the conventional manner. Thus at this stage of the weaving operation the threads A and B will be positioned below the weft thread F and the intermediate thread E will be positioned thereabove. Thereafter the weft thread F will be laid or beat into position in the conventional manner so as to occupy the position F' shown in Fig. 2. The intermediate thread E will be looped as illustrated in Fig. 3 and denoted by 68 and the weft thread F' will extend through said loop. As shown in Fig. 2, in a further stage of the weaving operation the heddles 40, 46 and 48 will be positioned to define the shed 62 and a suitable shuttle will be actuated to project the weft thread F'' therethrough. Thus the temporary weft thread F'' will be disposed between the threads C and D on one side and the intermediate thread E on an opposite side whereby it will be apparent 30 35 40 45 50 55 60 65 70 75 80 85 90 95

3
that the weft thread F'' is integrated with fabric 14 in a similar manner to the integration of the weft thread F' with fabric 12. Thereafter the apparatus will be operative to position the weft thread F'' to the position F''' as shown in Fig. 3 whereby it will be apparent that the temporary weft threads F' and F''' will support portions of the intermediate thread E relative to the fabrics 12 and 14. In Fig. 3 the heddles are shown disposed in a position so as to define the shed 64 through which a weft thread G is projected, said weft thread being shown positioned above thread B and below threads A and E. Similarly a weft thread G' will be projected through the shed 66 which is defined between the threads C and D of the fabric 14. Thus in the weaving stage illustrated in Fig. 3 the weft thread G will be interwoven with the threads A, B and E with the threads A and E positioned thereabove whereas the weft thread G' will be interwoven with the threads C and D with the latter thread being disposed outermost. In the next sequence of operations the position of the threads A, B and E relative to the weft thread G will be reversed whereby the thread B will be disposed outermost relative to said weft thread. Similarly the heddles 46 and 48 will be so disposed as to reverse the position of threads C and D relative to weft thread G' with thread C being disposed outermost relative to said weft thread. It is here to be noted that the looped portions 68 of the intermediate thread E are not interwoven with their associated fabrics 12 and 14 so that said looped portions are supported relative to said fabrics solely by the temporary weft threads F. Thus the portions 70 and 70' of the intermediate thread E are interwoven with the fabrics 12 and 14, respectively, during the weaving of the latter and portions 72, 74 and 76 of the thread E between interwoven portions 70 and 70' thereof are temporarily supported relative to the pair of fabrics 12 and 14. Thus the portion 70 of the intermediate thread E is interwoven with the fabric 12 and the portion 70' of said intermediate thread is interwoven with the fabric 14 with the portions 72, 74 and 76 of the thread E intermediate the interwoven portions 70 and 70' thereof being temporarily supported by the association of the looped portions 68 of said intermediate thread with the temporary weft threads F as aforescribed. It is to be noted in the aforescribed embodiment the weft threads F are disposed outwardly of the fabrics 12 and 14 of the mattress fabric 10.

After the aforescribed weaving operations are completed to form fabric 10', the weft threads F are removed in any desired manner whereby to release the looped portions 68 of thread E from temporary support relative to the fabrics 12 and 14. On the removal of the supporting weft threads F the thread portions 72, 74 and 76 may be expanded so as to define the transversely extending intermediate thread 16, shown in Fig. 5. Thus in the illustrated embodiment the fabrics 12 and 14 may be expanded to substantially three times the spacing corresponding to the width of the series of gages 22. It will be readily apparent that any desired spacing between the fabrics 12 and 14 may be obtained by the aforescribed method, which is given by way of illustration only. Thus the removal of the supporting weft threads F will permit the expansion of the fabric 10' to the condition 10 as shown in Fig. 5. Accordingly the sole function of the weft threads F is to temporarily support the looped portions 68 of the intermediate thread E so that the portions 72, 74 and 76 of said intermediate thread may be expanded on the removal of said weft threads to define the intermediate thread 16 which is of a length that substantially corresponds to three times the width of the gages 22.

From the above it will be apparent that warp and weft threads are interwoven to simultaneously form the pair of fabrics 12 and 14 which are disposed in laterally spaced confronting disposition with the spacing corresponding to the width of the series of gages 22 prior to

5 the removal of weft threads F. The intermediate thread E is woven with the warp and weft threads of the pair of fabrics 12 and 14, respectively, in succession, during the weaving of said pair of fabrics with said thread extending transversely between said pair of fabrics.

With reference to Fig. 6, there is shown a slightly modified form of fabric 10'' which is woven similar to the fabric 10 aforescribed except in the respects now to be specifically described in detail. The thread portions 68' of the intermediate thread E are looped in a conventional manner and the weft threads f and f' are projected through said looped portions whereby it will be apparent that said weft threads will be disposed inwardly of the fabrics 12 and 14 and outwardly of the gages 22 for support by the latter. Accordingly when the weft threads f and f' are released from support by the edges 23 of the gages 22 the fabrics 12 and 14 may be laterally spaced apart substantially corresponding to the condition 10 shown in Fig. 5. Thus the threads f and f' are released from support by the gages 22 when the fabric material is drawn therefrom so as to permit the increase of the lateral spacing between the fabrics 12 and 14 as aforescribed. Accordingly in the embodiment illustrated in Fig. 6 it is not necessary to remove the weft threads f and f' as said threads will be disposed between the fabrics 12 and 14 and will be accordingly hidden from view in finished articles formed from the fabric material 10. Thus in the embodiment illustrated in Fig. 6, portions of the thread E intermediate interwoven portions thereof are temporarily supported relative to the fabrics 12 and 14 by means of the gages 22 so when the fabric material is drawn from said gages the weft threads f and f' will be released from support thereby whereby to permit the increase of the lateral spacing between the fabrics 12 and 14. As aforescribed the fabrics 12 and 14 may be spaced apart any desired distance and the aforescribed specific embodiments are given by way of example and not by way of limitation.

40 The fabric material 10 may have the pair of fabrics 12 and 14 coated or impregnated with any suitable fluid impervious material such as latex, plastic, or the like whereby articles fabricated from said material will be fluid impervious. Thus, as shown in Fig. 7, the area 11 of fabric 10 is suitably coated with a fluid impervious material whereby it will be apparent that articles fabricated of such material will be fluid impervious. As shown in Fig. 1, the fabric 10' leaving the gages 22 will be drawn by a suitable take-up roll 78 which is positioned forwardly of the series of gages 22.

45 Any suitable threads may be used to form the fabric material 10 and the latter may be used to form a multitude of articles, for example inflatable mattresses and inflatable containers. Thus the fabric 10 may be fabricated to form containers for carbon dioxide and the like for fire extinguishing purposes or said containers may be used to contain fuel such as gasoline and the like. It will be understood that the aforescribed mattress fabric 10 readily lends itself to the formation of containers and the latter will use less material for a given volume than the heretofore used containers of this character in that said containers may be formed of a substantially greater depth without the integration of a plurality of such containers which must utilize more material for the same volume. Thus the aforescribed method readily lends itself to the formation of individual containers which have a depth which is not limited to a depth corresponding to the widthwise dimension of the gages 22.

50 Thus the aforescribed mattress fabric 10 is formed of a pair of fabrics 12 and 14 which are spaced apart a distance substantially greater than the width of the series of gages 22 on the loom 20 on which said fabric is made. It will be understood that the loom 20 on which the fabric material 10 is made is conventional in all respects and said fabric material may be made on any conventional weaving apparatus such as a Dobby or

Jacquard loom or any other loom having conventional shed control apparatus.

While I have shown and described the preferred embodiment of my invention, it will be understood that various changes may be made in the present invention without departing from the underlying idea or principles of the invention within the scope of the appended claims.

Having thus described my invention, what I claim and desire to secure by Letters Patent, is:

1. The method of making a fabric material formed of a pair of woven fabrics having an intermediate thread extending therebetween and woven thereto, comprising the steps of interweaving warp and weft threads to simultaneously form a pair of fabrics disposed in laterally spaced confronting disposition, weaving said intermediate thread with said warp and weft threads of said pair of fabrics, respectively, in succession during the weaving of said pair of fabrics with said thread extending transversely between said pair of fabrics, temporarily supporting portions of said thread intermediate interwoven portions thereof relative to said pair of fabrics by means of weft threads disposed outwardly of said fabrics, and thereafter removing said last mentioned weft threads whereby to release said portions from said temporary support whereby to permit an increase of the lateral spacing between said pair of fabrics.

2. The method of making a fabric material formed of a pair of woven fabrics having an intermediate warp thread extending therebetween and woven thereto, according to which there is employed a loom having warp-wise extending spacing means for holding said fabrics in initially spaced apart confronting relation; said method comprising the steps of interweaving warp and weft threads to simultaneously form a pair of fabrics disposed in laterally spaced confronting disposition at opposite sides, respectively, of said spacing means, weaving said intermediate thread with said warp and weft threads of said pair of fabrics, respectively, in succession during the weaving of said pair of fabrics with said thread extending transversely between said pair of fabrics, temporarily supporting portions of said thread intermediate interwoven portions thereof relative to said pair of fabrics by means of weft threads disposed inwardly of said fabrics at opposite sides, respectively, of said spacing means, and thereafter removing said last mentioned weft threads whereby to release said portions from said temporary support whereby to permit an increase of the lateral spacing between said pair of fabrics to a spacing greater than the initial spacing provided by said spacing means.

3. The method of making a fabric material formed of a pair of woven fabrics having an intermediate thread extending therebetween and woven thereto, comprising the steps of interweaving warp and weft threads to simultaneously form a pair of fabrics disposed in laterally spaced confronting disposition, weaving said intermediate thread with said warp and weft threads of said pair of fabrics, respectively, in succession during the weaving of said pair of fabrics with said thread extending transversely between said pair of fabrics, temporarily supporting portions of said thread intermediate interwoven portions thereof relative to said pair of fabrics by looping said thread portions and extending weft threads therethrough with the latter being disposed outwardly of said fabrics, and thereafter removing said last mentioned weft threads whereby to release said portions from said temporary support whereby to permit an increase of the lateral spacing between said pair of fabrics.

4. The method of making a fabric material on a loom having a series of gages disposed warpwise thereof with the material being formed of a pair of woven fabrics having an intermediate thread extending therebetween and woven thereto, comprising the steps of interweaving warp and weft threads to simultaneously form a pair of fabrics disposed in laterally spaced confronting disposition with said spacing corresponding to the width of

said series of gages, weaving said intermediate thread with said warp and weft threads of said pair of fabrics, respectively, in succession during the weaving of said pair of fabrics with said thread extending transversely between said pair of fabrics, temporarily supporting portions of said thread intermediate interwoven portions thereof relative to said pair of fabrics by looping said thread portions and extending weft threads therethrough with the latter being disposed outwardly of said fabrics, and thereafter removing said last mentioned weft threads whereby to release said portions from temporary support so as to permit a substantial increase of the lateral spacing between said pair of fabrics.

5. The method of making a fabric material on a loom having a series of gages disposed warpwise thereof with the material being formed of a pair of woven fabrics having an intermediate warp thread extending therebetween and woven thereto, comprising the steps of interweaving warp and weft threads to simultaneously form a pair of fabrics disposed in laterally spaced confronting disposition with said spacing corresponding to the width of said series of gages, weaving said intermediate thread with said warp and weft threads of said pair of fabrics, respectively, in succession during the weaving of said pair of fabrics with said thread extending transversely between said pair of fabrics, temporarily supporting portions of said thread intermediate interwoven portions thereof relative to said pair of fabrics by looping said thread portions and extending weft threads therethrough with the latter being disposed inwardly of said fabrics and outwardly of said gages at opposite sides, respectively, thereof for support by the latter whereby said last mentioned weft threads are released from support by said gages when said fabric material is removed therefrom so as to permit a substantial increase of the lateral spacing between said pair of fabrics to a spacing greater than the initial spacing provided by said gages.

6. The method of making a fabric material on a loom having a series of gages disposed warpwise thereof with the material being formed of a pair of woven fabrics having an intermediate thread extending therebetween and woven thereto, comprising the steps of interweaving warp and weft threads to simultaneously form a pair of fabrics disposed in laterally spaced confronting disposition with said spacing corresponding to the width of said series of gages, weaving said intermediate thread with said warp and weft threads of said pair of fabrics, respectively, in succession during the weaving of said pair of fabrics with said thread extending transversely between said pair of fabrics, temporarily supporting portions of said thread intermediate interwoven portions thereof relative to said pair of fabrics by looping said thread portions and extending weft threads therethrough with the latter being disposed outwardly of said fabrics, and thereafter removing said last mentioned weft threads whereby to release said portions from temporary support so as to permit a substantial increase of the lateral spacing between said pair of fabrics, and impregnating said pair of fabrics with a fluid impervious material so as to render said pair of fabrics fluid impervious.

7. A fabric material comprising a pair of woven fabrics having an intermediate thread extending therebetween and woven thereto, said pair of fabrics being disposed in laterally spaced confronting disposition with said intermediate thread transversely disposed therebetween, and means for supporting said thread intermediate woven portions thereof relative to said pair of fabrics whereby the release of said intermediate portions from support permits an increase of spacing between said pair of fabrics, said means comprising weft threads disposed outwardly of said fabrics, said weft threads extending through looped portions of said intermediate thread.

8. The method of making a fabric material formed of a pair of fabrics having an intermediate warp thread extending therebetween and connected thereto, accord-

ing to which there is employed a loom having warpwise extending spacing means for holding said fabrics in initially spaced apart confronting relation; said method comprising the steps of simultaneously weaving said pair of fabrics in spaced apart confronting disposition at opposite sides, respectively, of said spacing means, securing portions of said intermediate warp thread to said pair of fabrics at spaced intervals with said thread extending transversely between said pair of fabrics and interconnecting the latter, and temporarily supporting, by means of weft threads disposed at opposite sides, respectively, of said spacing means, successive portions of said thread intermediate successive secured portions thereof at points spaced from each other transversely of said pair of fabrics whereby the release of said intermediate portions from temporary support while said pair of fabrics are interconnected by said intermediate thread permits an increase of spacing between said pair of fabrics to a spacing greater than the initial spacing provided by said spacing means.

9. The method of making a fabric material formed of a pair of woven fabrics having an intermediate thread extending therebetween and woven thereto, according to which there is employed a loom having warpwise extending spacing means for holding said fabrics in initially spaced apart confronting relation; said method comprising the steps of interweaving warp and weft threads to simultaneously form a pair of fabrics disposed in laterally spaced apart confronting disposition at opposite sides, respectively, of said spacing means, weaving said intermediate thread with said warp and weft threads of said pair of fabrics, respectively, in succession during the weaving of said pair of fabrics with said thread extending warpwise of said pair of fabrics with portions thereof intermediate interwoven portions thereof extending transversely between said pair of fabrics and interconnecting the latter, temporarily supporting successive portions of said thread intermediate successive interwoven portions thereof at points spaced from each other transversely of said pair of fabrics, by means of weft threads disposed at opposite sides, respectively, of said spacing means, and thereafter releasing said portions from said temporary support while said pair of fabrics are interconnected by said intermediate thread whereby to permit an increase of the lateral spacing between said pair of fabrics as determined by said latter portions to a spacing greater than the initial spacing provided by said spacing means.

10. The method of making a fabric material formed of a pair of woven fabrics having an intermediate thread extending therebetween and woven thereto, according to which there is employed a loom having warpwise extending spacing means for holding said fabrics in initially spaced apart confronting relation; said method comprising the steps of interweaving warp and weft threads to simultaneously form a pair of fabrics disposed in later-

ally spaced confronting disposition at opposite sides, respectively, of said spacing means, weaving said intermediate thread with said warp and weft threads of said pair of fabrics, respectively, in succession during the weaving of said pair of fabrics with said thread extending transversely between said pair of fabrics, temporarily supporting successive portions of said thread intermediate successive interwoven portions thereof at points spaced from each other transversely of said pair of fabrics by means of weft threads, and thereafter releasing said last mentioned weft threads whereby to release said portions from said temporary support while said pair of fabrics are interconnected by said intermediate thread whereby to permit an increase of the lateral spacing between said pair of fabrics to a spacing greater than the initial spacing provided by said spacing means.

11. The method of making a fabric material formed of a pair of woven fabrics having an intermediate thread extending therebetween and woven thereto, comprising the steps of interweaving warp and weft threads to simultaneously form a pair of fabrics disposed in initial laterally spaced apart confronting disposition, weaving said intermediate thread warpwise of said fabric materials with said warp and weft threads of said pair of fabrics, respectively, in succession during the weaving of said pair of fabrics with said thread folded back and forth along lines extending between and perpendicular to said pair of fabrics and interconnecting the latter, temporarily supporting successive portions of said thread intermediate successive interwoven portions thereof at points spaced from each other transversely of said pair of fabrics by means of weft threads, and thereafter releasing said supporting weft threads whereby to release said portions from said temporary support while said pair of fabrics are interconnected by said intermediate thread whereby to permit an increase of the lateral spacing between said pair of fabrics to a spacing greater than said initial spacing.

12. A fabric material comprising a pair of woven fabrics interconnected in spaced apart confronting relation, made according to the method defined by claim 11.

13. A fabric material comprising a pair of woven fabrics interconnected in spaced apart, confronting relation, made according to the method defined by claim 1.

14. A fabric material comprising a pair of woven fabrics interconnected in spaced apart confronting relation, made according to the method defined by claim 5.
